Andrew D. Bochner(57) **CLAIM**

The ornamental design for an appliance interface, as shown and described.

DESCRIPTION

FIG. 1 is a top, front, left-side perspective view of an appliance interface, showing our new design;

FIG. 2 is a front elevation view thereof;

FIG. 3 is a left side elevation view thereof, the right side elevation view being a mirror image;

FIG. 4 is a top plan view thereof; and,

FIG. 5 is a bottom plan view thereof.

In the drawings, the broken lines are for the purpose of illustrating environment only, and form no part of the claimed design.
